ENAMELED TANK

Chalmer E. Murphy, Cleveland Heights, Ohio, assignor to Porcelain Steels, Inc., Cleveland, Ohio, a corporation of Ohio

Application November 25, 1940, Serial No. 367,075

1 Claim. (Cl. 220—55)

This invention relates to closed tanks and particularly to tanks of the domestic hot water supply type coated inside or inside and outside, with vitreous enamel.

In the manufacture of enameled tanks of the type referred to, unexpected problems arise the solution of which is not obvious. Such tanks in use contain hot water under pressure, and the hot water corrodes the metal wall of the tank and in a comparatively short period of use the wall becomes perforated by the corrosion and a leak results destroying further usefulness of the tank for its intended purposes. For a number of years it has been the practice to galvanize the tank's walls to resist such corrosion, but because the tank is a closed container, at the time that the coating is applied, it is next to impossible to produce a continuous solid galvanized coat on the inner wall by any known galvanizing method; and a single uncoated spot will corrode and become perforated in as short a time as if there were no coating at all.

The useful life of the usual galvanized hot water tank therefor is little if any longer than that of an ungalvanized one.

Metals and alloys having corrosion-resisting properties have been proposed for the walls of such tanks to prolong their life but such tanks are too expensive for the general market.

The cheapest and most practicable known fabricating process for making the tank walls, is to make the walls in pieces from sheet steel and to join them together; and to render such a steel tank corrosion proof, it has been proposed to coat the tank walls, particularly the inside wall, with vitreous enamel, that is to say enamel formed by firing and fusing dried enamel slip. The tank walls may be variously constructed but the applying of the enamel coat presents difficulties. The enamel coat must be absolutely complete and solid so as not to expose even a single uncoated spot of the steel wall however small to the corrosive action of the hot water; and for this reason, if welding be used in joining the steel parts of the wall, the welds must be contrived in some manner so that the enamel as applied will not contact the weld itself, because if it does it will not form solidly thereover, with the one exception of electric flash welding the flash of which has been toolled off down to solid metal.

Again, if parts of the wall are joined by riveting, spot welding, roll welding, etc., so that one part overlaps another with intermediate crevices, foreign matter which unavoidably finds its way into said crevices, or which is produced therein by

the welding operation, will vitiate the enamel coat during the formation thereof so that it will not form solidly or completely thereover. And if the joints between wall pieces are not perfectly rigid, one part will have movement relative to another when the tank is subjected to internal pressure, and even if such relative movement is so slight as to be imperceptible without delicate measuring instruments, it still is sufficient to crack the glass-like brittle enamel coat thereat and admit the corrosive hot water to the steel of the wall.

The general market and manufacturing facilities and economies demand a hot water tank of the form comprising an elongated cylindrical body and heads at each end of the body. If the body wall of such a tank, which for the sake of economy must be made of as thin metal as practicable, comprises any portions which are generally planar, or "out of round," they tend to become more truly cylindrical under the internal pressure and this deformation will crack the enamel; or if there are any curved wall portions of any shape which under pressure become straightened out by the longitudinal pressure on the heads which tends to stretch the body, their deformation also will crack the enamel. Cracking of the enamel at any point on the inner wall of the tank will start corrosion thereof.

It follows therefore that a successful enameled hot water tank cannot be arrived at by taking just any known steel-walled tank and attempting to coat it with enamel.

After many experimental attempts to make such a tank I have found that the above indicated problems can be solved and herein I have described the preferred construction and method of making such a tank.

The preferred construction comprises a cylindrical tubular body of relatively thin steel with a flash-welded longitudinal seam toolled off down to solid metal and the body trued up to cylindrical form; a heavy ring of steel surrounding the outside of the body and welded to it near each end, and the ends of the body flanged and coined over the rings; a pair of dished peripherally flanged heads of outwardly curved or generally ellipsoidal sectional form at each end of the body and of sufficiently thick sheet steel to resist deformation by internal tank pressure; and means to sealedly attach the heads to the ends of the body through the agency of the rings.

With the body parts thus made separately, they can each be enameled separately and the enamel coat thoroughly inspected for imperfections before the parts are assembled in the completed

tank; and the formation of a perfect enamel coat is facilitated during the enameling process; and all liability of enamel cracking during assembly or by internal pressure after assembly is avoided.

The present invention relates particularly to means by which the enameled heads of such a tank are attached to the enameled body.

It is among the objects of this invention therefore:

To provide generally an improved construction of enamel-coated tank for containing fluid such as hot water under pressure;

To provide improved means for attaching an enameled tank head to an enameled tank body;

To provide improved means for attaching an enameled tank head to an enameled tank body which allows for variation in the dimensions of the head and body which occur during the manufacture thereof;

To provide an improved construction of clamping device or means for clamping the enameled peripheral flange of a tank head upon the enameled peripheral flange of a tank body with sealing gasket material therebetween to effect an improved internal pressure-proof and leak-proof juncture between the head and the body;

To provide in connection with a head clamping construction such as referred to above, improved cover means to cover and conceal the same.

Other objects will be apparent to those skilled in the art to which my invention appertains.

My invention is fully disclosed in the following description taken in connection with the accompanying drawings in which,

Fig. 1 is a side elevational view partly broken away of a tank embodying my invention in one form;

Fig. 2 is a top plan view of the embodiment of Fig. 1;

Fig. 3 is a fragmentary longitudinal sectional view to enlarged scale of a part of the tank of Fig. 1 illustrating in the preferred form a means of attaching a head to a tank body and a cover element for covering the attaching means;

Figs. 4 and 5 are views similar to Fig. 3 illustrating a modification and the mode of operation thereof to compensate for dimensional variations which may occur in the construction of the parts of the tank;

Fig. 6 is a view similar to Fig. 3 illustrating another modification;

Fig. 7 is a view illustrating a modification of a bolt device which I may employ, one form of which is shown in Figs. 4 and 5;

Fig. 8 is a view taken in the direction of the arrow 8 of Fig. 7;

Fig. 9 is a view similar to Fig. 7 illustrating another modification;

Fig. 10 is a view taken in the direction of the arrow 10 of Fig. 9;

Fig. 11 is a view similar to Fig. 3 but illustrating another modification;

Figs. 12 and 13 are views illustrating the mode of operation of the modification of Fig. 11 to compensate for dimensional variations which may occur in the construction of the parts of the tank;

Fig. 14 is a view illustrating steps of the process which may be employed in the formation of a clip device shown in Fig. 11;

Fig. 15 is a view similar to Fig. 3 showing the head-attaching means of Fig. 3 for the head at the opposite end of tank;

Figs. 16, 17 and 18 are other views similar to Fig. 3 showing other modifications.

Referring to the drawings, Figs. 1 and 2, wherein I have illustrated one form of a tank embodying my invention, at 1 is indicated the main body of the tank, the same being of cylindrical form, and at 2 and 3 are illustrated heads at each end of the body 1, the heads being generally of oval or hemi-ellipsoidal form in cross-section. 10 Conduits may be connected to the tank wall in communication with its interior, illustrative of which are the conduits 4-4 connected to the head 2.

The body 1 is preferably constructed by rolling 15 a sheet of steel into the form of a hollow cylinder and flash welding the abutting edges thereof together at a longitudinal joint indicated at 5 in Fig. 3. A heavy steel ring 6 is tack welded or spot welded to the outer wall of the body 1 inwardly of the end of the body and then the end of the body is bent and coined over the ring 6 to form a flange 7.

The ring 6 has preferably a corner 8 which is coined into the metal of the wall where the flange 7 joins the cylindrical body 1, and the cylindrical body 1 is then trued up to remove any planar or out of round portions. Rings 6 and flanges 7 are provided on each of the opposite ends of the body 1, and by the fabricating process employed, when the opposite end heads 2 and 3 have been attached to the body wall through the agency of the rings 6, and internal pressure exerts longitudinal tension in the wall 1, there is no part of the wall which is out of round or which 35 tends to straighten out in the axial direction, and deformation is prevented, for the purposes referred to.

After the flash has been trimmed off from the weld 5 down to solid metal and any other roughness on the wall of the body 1 flange 7 or ring 6 has been removed, the body flange and ring are coated with a coat of vitreous enamel 9.

The heads 2 and 3 may be alike except in some cases as to a different number of conduits 4 connected thereto. The head 2 as shown in Figs. 1 and 3 is generally of hemi-ellipsoidal cross-sectional form having a peripheral flange 10 lying substantially in a plane transversely of the head and continuing peripherally into a depending skirt 11. The flange 10 has a circular series of bolt perforations 12 therein the series being substantially concentric with the axis of the head.

The head including the flange 10 and skirt 11 are coated inside and out with a coat of vitreous enamel 13, the perforations 12 being provided either before or after the enameling process.

By making the body separate from the two heads and enameling the three parts separately, the formation of an unbroken solid coat of enamel is facilitated inasmuch as oxygen-containing air is free to flow over all the surfaces being enamel-coated. This free flow of air facilitates drying the wet enamel slip uniformly and without sweating and during the firing of the dried slip the essential presence of oxygen on all parts of the surfaces of the pieces is readily attained. Forming the pieces separately permits a thorough inspection of the enamel coat thereon for accidental imperfections.

To assemble the head with the body, a sealing gasket 14 is laid on the flange 7, and the head flange 10 superimposed thereon and the head flange is clamped upon the body flange with the 75 gasket therebetween by the following means.

Bolts 15 are projected downwardly through the perforations 12 and their lower ends are threaded into washers or plates 16 overlapping and bridging the under side of the enameled ring 6 and the lower termination of the skirt 11. The bolts 15 are then turned by their heads 17 and by the clamping action exerted between the heads and the plates 16, the head flange 10 is drawn down tight upon the body flange 7 to effect a pressure-proof and liquid-tight seal at the gasket 14.

The skirt 11 performs a number of functions. Since the bolts 15 are radially outward beyond the gasket 14, the latter acts as a fulcrum over which the flange 10 tends to bend and it might bend and crack the enamel on the flange if it were not for the skirt 11, but the presence of the skirt prevents such bending because in order for the flange 10 to bend the skirt 11 would have to be compressed or deformed, and the skirt 11 being disposed at right angles to the plane of the flange 10 it acts as a beam of relatively great depth and gives rigidity to the flange 10 and prevents it from bending. This is important because bending of the flange 10 would crack the enamel.

Again, since the gasket 14 is compressible, and since the bolts 15 must be spaced one from the other in their circular series, the force of the bolt heads 17 would tend to force the flange 10 into the gasket 14 at points opposite the bolts and allow it to remain bulged upwardly at points between the bolts and this would tend to crack the enamel, but the skirt 11 contributes such rigidity to the flange 10 that this action and enamel cracking is prevented. Again, the skirt 11 at its lower peripheral edge provides a base upon which the plate or washer 16 engages for the clamping purposes described above. Again, the skirt 11 covers the bodies of the bolts 15 and conceals them, rendering neat in appearance what would otherwise be a complicated appearing bolted structure.

The under sides of the heads 17 of the clamping bolts, may be generally spherical as indicated in Fig. 3 so that they will engage the perforations 12 on the end edges thereof and thereby prevent mutilation of the enamel as the bolts are turned.

The diameter of the skirt 11 is made dimensionally such that a space 18 may preferably be left between the bolts and the enamel coat on the ring 6 and so that a space 19 may be left between the bolts and the skirt 11, and the perforations 12 are located on a circle of such diameter that the bolts will extend downwardly between the skirt and the ring so that these spaces 18 and 19 will be substantially equal.

A number of advantages accrued from the employment of the construction described above which are not apparent without further consideration. In the making of the head 2 by the usual press-forming operation, strains are set up in the metal. When the enamel coat is applied the metal is heated to at least a cherry-red color so that the heads tend to warp. The flange 10 may warp slightly out of a true plane, or if it is all in one plane it may warp slightly out of parallelism with planes at right angles to the axis of the body or of the head itself, and the skirt 11 may warp slightly out of cylindrical form. Similarly the ring 6 and body 1 may warp slightly out of round and slightly out of planar form at the ring and flange 7. Again, the perforations 12 may not lie exactly on a circle or upon a center line circle of exactly pre-selected diameter, and

if accurate die means is used to punch such perforations they may not lie in their pre-selected positions after the head is enameled because of the above-mentioned warping which may take place.

By means of the above-described construction which includes the spaces 18 and 19, considerable tolerance in the dimensions and shapes referred to is permitted and therefore although, 10 out of a number of heads and bodies, no two heads and no two bodies may be exactly alike, any two heads may be mounted as described upon any of the bodies, and thus complete interchangeability is provided notwithstanding that the 15 allowable tolerances are very great, both as to accuracy in making the parts in the first instance and as to warpage due to subsequent heating.

While the warpage referred to is not of sufficient degree to cause the wall or head to deform under pressure in use and crack the enamel coat, it may be enough to interfere with assembly of the parts, if such tolerances are not provided.

If desired, the joint structure above-described 25 in connection with Fig. 3 for the upper head may be made still more neat in appearance by the following means. A sheet metal cover 20 is press-formed or spun from sheet metal, which may be light in gage, and comprising a planar cup bottom 21 and a cup skirt 22. A large perforation 23 is made in the cup bottom. After the head has been attached to the body or after the tank has been installed, or brought to the place of installation, the perforation 23 is telescoped over 30 the upwardly curving part of the head as shown with the skirt 22 depending around and covering all of the parts of the joint and the cup bottom 21 may rest upon the heads 17 of the bolts to support the cup-form element as a joint cover. 35 The cup-form element 20 may be externally plated or plated and polished if desired or it may be enamel-coated and of the same or of a different color from the external enamel 9 and 13 giving a very neat and ornamental appearance to 40 the entire structure, and since the head 2 is enameled separately from the body 1, it may have a different color from that of the body.

In Fig. 15 this same joint structure of Fig. 3 is illustrated for the lower head 3 and a cup form cover device 24 may be provided having a skirt 25 with the bottom of the cup resting upon the ends of the bolts 15 as shown in Fig. 15. The cover device may be put on before the head is attached.

55 In Fig. 6 is illustrated a modification of the clamping means. Here instead of the bolt 15 and plate or washer 16 of Fig. 3, a J-bolt 26 is used, the short leg 27 of the J engaging the under side of the enameled ring 6, the long leg of the J extending upwardly through the perforation in the flange 10 and having threaded thereon a nut 28.

In attaining cheap quantity production of 65 tanks such as that described above other large tolerances beside the dimensional and warpage tolerances above-mentioned may be desirable such for example as tolerances in the thickness of the packing washer 14 and of the amount which it compresses when clamping pressure is put thereon; tolerances in the axial length of the skirt 11 and tolerances in the axial over-all dimension of the ring 6 and flange 7. When such tolerances are wanted, the construction of 70 Figs. 4 and 5 may be employed. The general 75

construction is the same as that of Fig. 3 except that the bolt in this case 29 is projected downwardly through the flange 10 with the head 30 of the bolt resting on the flange, and with a nut 31 on the lower end of the bolt below the plate or washer 16, and the nut having if desired a rounded or spherical under side as shown at 32 in engagement with the plate 16. The plate 16 is in this case provided with a perforation through which the bolt extends loosely and as the nut 31 is drawn up tight, the plate will assume the right angle position with respect to the bolt indicated in Fig. 3 or will rock one way or the other into bridging and clamping engagement with the skirt 11 and ring 6 as shown in Fig. 4 or Fig. 5 depending upon whether in the final assembly the combined thickness of the ring 6 and flange 7 and the packing washer 14 brings the lower side of the ring 6 below or above the peripheral edge of the skirt 11.

Instead of the bolt and nut arrangement of Figs. 4 and 5 the bolt and nut arrangement of Figs. 7 and 8 or that of Figs. 9 and 10 may be employed the construction and mode of operation of which it is believed will be apparent without further description from the above-detailed description of Figs. 4 and 5.

In Fig. 11 is illustrated a further modification which in addition to the above-described tolerance advantages has a centering action and an inter-locking action. As shown in Fig. 11 the ring, in this case 6A has the under side 33 thereof formed generally conical sloping inwardly upwardly, the ring on the opposite end of the body sloping inwardly downwardly as will be understood. The clamping plate 34 has a main body portion 35 engaging the lower edge of the skirt 11 and for average tolerances being horizontally disposed and has an angularly offset end portion 36 engageable with the under side 33 of the ring 6A. A nut 37 rounded on its under side and engaging the plate 34 is threaded on the bolt 38. When the nut is drawn tight, the plate 34 bridges the skirt 11 and ring 6A as described above and the offset portion 36 of the plate interlocks with the ring. When all of the plates and bolts have been drawn up circumferentially of the structure this interlock prevents lateral shifting of the head with respect to the body and centers the head with respect to the body. If an accumulation of the above-mentioned tolerances causes the plate body 35 to take up an inclined position, the plate may assume the position of Fig. 12 or that of Fig. 13 as described above.

The plate 34 may be made from a sheet or strip of metal 39 as shown in Fig. 14 by first perforating it as shown at 40-40 and then shearing it transversely as at 41-41 and then bending portions 36-36 out of the plane of the strip, the plate in such event being generally U-shaped whereby it may be assembled with the bolts 38 by lateral movement after the nut 37 has been run loosely on the bolts. The bolts 38 may thus be put in the head loosely before the head is brought to the position to be assembled with the body which shortens the assembly time for assembling the bolts with the head.

Obviously a U form plate with or without the offset portion 36 may be used with others of the forms described and to be described. The inclination from the horizontal of the plates in Figs. 4, 5, 12 and 13 is exaggerated in the drawings to more clearly illustrate the principle.

In the foregoing I have illustrated and described my invention in its preferred embodiment,

ments, and in Figs. 16, 17 and 18 I have shown further modification embodiments which I may employ in the practice of my invention when desired.

5 As indicated by the construction in Fig. 16, the body 1 may at the gasket-engaging end thereof be variously formed. It may terminate without the above-described flange 7 as shown at 42, or the end may be rolled or folded over as indicated 10 in broken line at 43. In the above-described preferred form, the under side of the ring 6 provides a shoulder against which the bridging washer or plate 16 engages and as indicated in Fig. 16, this shoulder may be provided otherwise 15 for example by pieces such as 44, corresponding in number to the plate 16 and welded to the outer wall of the body 1 inwardly of its end.

In the modification of Fig. 17 the ring 6 and flange 7 are provided as before, the under side 20 of the ring 6 providing the said shoulder, but here the bridging element 45 is in the form of a ring surrounding the body 1 and the central opening 46 of which is large enough so that when the ring is shifted to one side it may be telescoped over the ring 6 and then centered around the body 1 whereby it will engage the under side 25 of the ring 6 as a shoulder, and the bolts 47 are threaded into the body of the ring to effect the clamping action.

30 In the modification of Fig. 18, a ring 6B is provided over which the flange 7 is bent and into the corner 48 of which it is coined as referred to above. The ring 16 may be welded to the flange 7 as indicated at 49. The ring 6B which 35 surrounds the body 1 may be of sufficient radial extent as shown to engage both the under side of the flange and the peripheral termination of the skirt in this case 11A, the flange 7 itself constituting the shoulder means and the ring 6B 40 constituting the bridging means by which the clamping action of the bolts 50 is effected.

A consideration of the forms of Figs. 16, 17 and 18 in connection with the preceding forms more completely described, show that with respect to 45 the clamping of the head upon the body to effect a seal at the gasket the structure comprises any form for the end of the body which engages the gasket a specific form being a flange such as the flange 7; and shoulder means of some kind 50 on the body which may be the under side of the ring 6 or the under side of the flange 7, the latter as in Fig. 18, or separate abutments such as 44 in Fig. 16; bridging means between the skirt 55 of the head and the shoulder means which may be separate washers or plates 16 or which may be a ring as in Figs. 17 and 18. And the various modifications illustrated and described indicate that other forms of body and shoulder means and bridging means may be provided by other 60 modifications and by changes and combinations of the forms shown so that my invention is not limited to the exact details of construction illustrated and described but is inclusive of all such 65 modifications and changes which come within the scope of the appended claim.

I claim:

In a tank construction a tubular tank body, a ring surrounding the body adjacent its end and welded thereto, a flange on the end of the body extending outwardly radially over the ring, a head having an annular substantially planar portion opposite the flange, a compressible yieldable gasket between the annular head portion and the flange, a skirt on the head surrounding the flange

and ring and radially spaced therefrom, a circular series of bridging elements bridging the ring and the skirt, and a circular series of threaded bolts disposed in the space between the ring and the skirt and projected through perforations in the planar portion and the bridging elements and provided with heads and nuts to exert a clamping action on the bridging elements and planar por-

tion to clamp the gasket between the head and the flange, a coat of vitreous enamel on the planar portion, and the skirt being sufficiently rigid to prevent bending of the planar portion and cracking of the enamel coat by the clamping action at the bolt perforations therein.

CHALMER E. MURPHY.
